FABRIC PRESSING APPARATUS

John E. Preston, Cincinnati, Ohio, assignor to
 The American Laundry Machinery Company,
 Norwood, Ohio, a corporation of Ohio

Application October 24, 1941, Serial No. 416,333

17 Claims. (Cl. 38—10)

The invention relates to automatic continuous pressing machinery of the conveyor type. It relates particularly to novel and improved control mechanism for flatwork ironing machinery wherein conveying means moves work pieces into and out of registry with coacting pressing elements which are adapted to engage the work for a predetermined period, while said work is positioned on the conveyor.

The apparatus is especially adapted for ironing handkerchiefs, napkins, or pieces of that general nature. It includes an endless conveyor, herein-after termed an apron, one run of which passes between the pressing elements. Means are provided for maintaining the apron at rest during the pressing period, thereby permitting the operator to arrange the work for the next succeeding pressing operation. Further means are provided, associated with said apron, for initiating relative movement of the pressing elements into pressing relationship, and, further, for controlling the period of the pressing operation.

The apparatus is further provided with means for separating the pressing elements at the termination of said pressing operation and thereafter advancing the apron a predetermined amount to clear the finished work from between the pressing members and to carry the next lay of work to registration therebetween, said lay having been previously arranged as aforesaid by the operator.

I have further provided means whereby, on completion of a pressing operation and separation of the pressing elements, the automatic advance of the apron is temporarily prevented if the operator is still arranging the next lay.

I have further provided, for said apron, driving means designed to reduce or eliminate apron stretch which has heretofore been encountered as a result of the usual driving systems where the apron passed over a powered driving roll.

I have further provided means for maintaining an even tension on the apron, said means being simultaneously designed to afford a backing support to that portion of the apron upon which the operator arranges the lay next to be ironed.

I have further provided means whereby, immediately after the pressing operation, each successive lay of ironed material is carried to a position where it is subjected to an after-drying effect produced by the heat from the ironing elements, the after-drying effect being coincident with the period of the succeeding ironing operation.

I have also provided, in conjunction with spaced electrical conducting elements carried by

5 said apron, electronic relay circuits sensitive to said conducting elements, and power operated means operatively responsive to said electronic relay circuits for determining the time of inception of a pressing operation and controlling the length of the pressing period. I have further provided said apron with a plurality of conducting and non-conducting segments following each other in predetermined, spaced sequence, where-
 10 by one complete passage of the apron between the coacting pressing surfaces may involve a plurality of pressing cycles. In the device illustrated in the attached drawings, and hereinafter described, the complete apron is provided with four equally
 15 spaced conducting zones, the passage of each between registered contacts serving to complete associated electronic tube circuits to initiate and control a pressing operation as aforesaid, with the result that one complete round trip of a point
 20 on the apron back to original position involves four successive pressing operations.

My invention also contemplates the provision of operator operated controls whereby a pressing operation may be terminated at any time desired
 25 by the operator, regardless of the position of any of the automatic control elements herein described.

In the drawings,

30 Fig. 1 is a side elevation of the press apparatus, the operator's working position being at the right of the drawing.

Fig. 2 is an enlarged fragmentary sectional view taken on the line 2—2 of Fig. 4 showing the electrical conducting portion of the apron in position between an upper conducting plate and a lower conducting finger.

Fig. 3 is a section taken on the line 3—3 of Fig. 1, some parts being broken away to show internal construction.

40 Fig. 4 is a section taken on the line 4—4 of Fig. 1.

Fig. 5 is a section, partially broken away, taken on the line 5—5 of Fig. 3.

45 Fig. 6 is a section taken on the line 6—6 of Fig. 1.

Fig. 7 is a fragmental plan view of a part of the apron showing the metal lacing which functions as an electrical conducting portion of the apron.

50 Fig. 8 is a diagrammatic view of the pressure fluid operating mechanism and air circuits.

Fig. 9 is a diagram of the electrical control circuits including the electronic tube circuits.

Fig. 10 is a fragmentary plan view, similar to

Fig. 7, but showing a control belt spaced from the apron.

Before proceeding to a more detailed description I may state, in general, that the ironing or pressing machine herein disclosed comprises two coacting pressing elements, either or both of which may be heated by any convenient means. These pressing elements are supported by a frame structure, and suitable power means is provided for moving the elements into and out of pressing engagement, one of the elements being, in the present instance, a stationary chest and one a movable buck. The upper run of a continuous apron passes between the pressing members and extends therebeyond a sufficient distance, upon suitable supporting means, to provide the operator with a convenient apron area upon which to arrange the pieces next to be pressed. The lower run of the continuous apron is maintained in frictional contact with one or more endless driving ribbons which pass over a driving roll. From previous experience it has been determined that a direct drive applied to the apron itself results in a tendency, increasing with time, to permanently stretch the apron, thus necessitating continuous readjustment of the apron length. In the present design it is only necessary to maintain the driving ribbons under constant tension.

The apron in the embodiment herein disclosed is assembled from four end-to-end sections united by belt connecting means at the abutting ends, said means being largely metallic so as to constitute electrical conductors. At a convenient location in the path of travel of the apron two electrical contact members are provided, one above and one below the apron and in frictional contact therewith, so that when apron travel carries the said metallic portion of the apron between the contacts a circuit is established which controls the time of initiation of operative contact between the pressing members. In the present embodiment it is apparent that this occurs four times in a round trip of the apron.

As the movable pressing unit advances to pressing position a control member associated therewith temporarily interrupts the apron drive, said drive thereafter remaining inoperative on the apron until the pressing operation is completed. The apron then advances until the next conducting area passes between the contacts to thereby initiate the next pressing operation, the articles already pressed being advanced by the belt to an after-drying position, as will appear.

The actual duration of the pressing operation is automatically timed by a sensitive and accurate electronic timing and relay device which energizes or deenergizes power means for instituting or terminating the pressing operation, the apron drive being rendered temporarily inoperative during the pressing operation, as aforesaid.

General construction

The general framework of the machine comprises four standards or legs 10, suitably tied together by rods 12. At the top of each leg there is an extending bracket 11, the four brackets forming a supporting means for a spiderlike bracket 13 which supports a fluid motor 28. The brackets 11 and each branch member of the motor supporting bracket 13 are bored out to receive rods or posts 14. The lower ends of the posts are of reduced diameter to form a shoulder which engages the top face of each of the branches of the motor supporting bracket 13. The lower ends are

threaded and a nut 15 is provided to securely anchor the posts 14 to the said bracket.

The posts 14, so arranged, form a support for the ironing chest 16. To support this chest, the upper ends of the posts are of reduced diameter to form a shoulder upon which the chest rests and the upper ends are threaded and provided with nuts 16 to securely anchor the chest on the posts.

10 The buck member 18 lies beneath the chest and is movable relative thereto by means of sleeves 19 slidable on said posts and forming an integral part of the buck casting.

15 A yoke member 22 is secured, at each end, to the underside of the buck by means of bracket extensions 20, as shown in Figs. 1 and 3. This yoke member is formed at the center to provide a post or abutment 23 which is adapted to be engaged by the piston rod 29 of the pressure producing fluid motor 28 to move the buck into pressure engagement with the chest. The yoke member 22 is recessed, as shown at 27 in Figs. 1 and 5 to receive a bar 30 which extends the full length of the yoke and beyond each end as shown in Fig. 3 and is supported by a rod 32 at each end, the bar resting on collars 33 pinned to said rods. These rods, in turn, are supported by bracket extensions 17 of the chest to which they are pinned, and a compression spring 31 is interposed between the bracket extensions and the bar to normally bias it downwardly against the collars 33. As shown in Figs. 1 and 3, in the normal open position of the buck, there is a clearance between the lower face of the bar and the upper face of the yoke member providing a space through which the lower run of a set of ribbons 34 is free to move when the buck is in open position. The upper face of the yoke member is provided with a series of nodes 24 which act as guides for the ribbons 34. When the fluid motor is energized to move the buck into pressure engagement with the chest, the bar 30 remains stationary during the first increment of this movement so that the clearance between the bar and the yoke member is thereby closed. When the space is fully closed a pressure is applied between the bar and the upper face of the yoke member to hold the ribbons against movement. In the further movement of the yoke and buck unit into engagement with the chest, the bar moves with the said unit as permitted by compression of the springs 31.

55 The yoke 22 is also provided with an abutment 25 which in its lowermost position contacts the stem 36 of an air valve 35. As shown in Fig. 8, this valve is a combination inlet and exhaust valve and, when the buck is in the lower or open position, it is normally held by abutment 25 in an inlet-open exhaust-closed position. This valve, as will be later described in more detail, controls the drive for the ribbons 34. The first increment of upward movement of the buck permits this valve to close, and the timing, relative to the holding effect of the bar 30 on the ribbons, is such that the drive for the ribbons is disconnected simultaneously or slightly before the ribbons are gripped between the yoke 22 and the bar 30.

70 The buck is provided with the usual padding 74 (see Fig. 3). The padding arrangement comprises a metal plate 75 which covers the buck. This plate extends beyond the side edges of the buck and is supported by angle brackets 76. Secured in the extending edges of the said plate are a number of protruding pointed screws 77. The padding is placed on top the metal plate and the cover cloth is placed thereover and the side

edges pushed down over the pointed screws 71 and a bar 71 is then placed over the said screws on top of these edges of the cover, and nuts 78 are supplied to hold the bars and the cover securely in position.

A bracket member 37 (Fig. 1) is fixed to the top of each of the front legs 10. These brackets cooperate to support the rear edge of a table 38 which extends forwardly and is inclined downwardly and is supported at its front edge by a pair of brackets 40, which, in turn, are mounted on a pair of bracket arms 42 secured respectively to the front side of two front legs 10. The side edges of this table extend downwardly in the form of flanges 39 which are adapted to support a conducting plate 43. It also supports a bracket 44 which is adapted in turn to support a pair of conducting fingers 45, the function of which will be described later in more detail.

Numerical 51 designates a light gauge spring steel plate which is substantially the dimensions of the inclined table. This plate is secured to the framework against the table at the upper end thereof, as shown. It extends forwardly and is turned downwardly at 41 along its forward edge so that, when the plate is flexed downwardly, it extends over the front downwardly extending flange of the said table. Normally this plate would extend substantially horizontally from its fixed point, but when the conveyor apron, to be described below, is in position this plate is flexed downwardly producing a biasing pressure from within, and against the endless apron, which tends to maintain the apron taut. In other words, the plate functions as an apron take-up device.

Conveyor apron and its ribbon drive

The conveyor apron and drive arrangement, now to be described, is of a type which reduces apron stretching to a minimum. In spite of this, there is always a small amount of apron stretch which takes place during the life of an apron. The said plate by reason of its biasing pressure as aforesaid provides a take-up device for this stretch. It also serves in the beginning, when a new apron is applied, to provide a substantially constant tautness.

Numerical 46 designates a wide conveyor belt or apron, the upper run of which moves over the take-up plate 51 over table 38 and over the top surface of the buck 18 and is guided around the rear edge of the buck by a smooth curved flange plate 48 supported by the buck. If desired an idler roll may be substituted for plate 48. The lower run extends forwardly below the buck and over a roll 49 journaled in the brackets 31 and thence forwardly beneath the table 38 and between the conducting fingers 45 and the conducting plate 43 and around a roll 50 journaled in the brackets 40. This apron serves as a conveyor for the article to be pressed. Such an article is dressed on the apron over the plate 51 and table 38 and thence is conveyed by the apron to position over the buck whence, by operation of the buck as aforesaid, it is moved upwardly into engagement with the chest, and pressure is applied to iron it.

The apron 46 is made up of a number of sections and these sections are attached in a continuous strip by metal lacings 47 to form a conveyor. The metal lacing 47 functions as a part of the control circuit in association with the conducting plate 43 and the conducting fingers 45, said plate and fingers being in frictional contact respectively with the upper and lower apron surface as will be later described.

The upper run of the ribbons 34, previously referred to, is in direct contact with the lower run of the said apron. These ribbons run over a driving roll 52 and thence under an idler roll 53 journaled in a pair of brackets 54, fixed respectively to the top of each of the rear legs 10, and extend forwardly through the previously referred to clearance space between the bar 30 and the yoke member 22, thence around an idler roll 55, over a roll 56 journaled in the brackets 40, and thence into contact with the apron 46 and around the roll 50 and over the roll 49 to the drive roll 52. The supporting arms 57 for idler roll 55 are respectively pivotally supported on the brackets 40 and are provided with an adjusting screw and nut 58. It will be noted that movement of the apron is accomplished solely through its frictional contact with the driving ribbons.

Clamping bar and foot control

Numerical 59 designates generally an article clamping bar. As shown in Figs. 1 and 4, this comprises a pair of arms 60 which are pivotally connected, respectively, to the chest casting at each side thereof and they are connected at their front by the bar member 62 which supports a holding strip 61 preferably made of Bakelite, hard rubber or like composition. This clamping bar unit is connected by a rod 63 with a foot pedal generally designated 64. The foot pedal comprises a pair of arms 65 connected, respectively, to each front leg. These are connected at the front by a foot plate 66. The right arm has an upward extension 67, the top end of which is bored to receive a rod 69 which is threaded at its one end and provided with a nut 70. The other end of the rod 69 is connected to a spring 72, the rear end of which is anchored to a stud 81 in one of the cross rods 12. This constitutes the biasing means to hold the pedal and clamp in idle position. The upright 67 is provided with an extension 68 which is adapted to actuate a combination air valve 73 supported by the right leg. This air valve as will appear is also in the air circuit controlling the ribbon driving mechanism, and, as shown in Fig. 8, is in series with the valve 35.

The purpose of the clamp is to hold the article in position while it is being smoothed off in a dressing operation. These parts are all arranged relative to the movement of the pedal so that the valve 73, which is normally held open to transmit fluid pressure therethrough when the pedal is in the idle, spring biased position, is closed immediately prior to the clamping member reaching engagement with the article when the pedal is depressed. When the pedal is released the clamp is completely removed from the article prior to the reopening of the valve and apron movement is therefore unobstructed before the driving mechanism is connected. This function is also associated with the operation of the machine as will be later described in more detail.

As already disclosed the apron drive is accomplished by frictional contact between the lower run of the apron and the upper run of a plurality of driven ribbons 34. In general, this drive embodies a continuously running electric motor between which and the ribbon drive roll is interposed a clutch. The apron is driven by frictional engagement with the ribbons. The said clutch is automatically engaged and disengaged to intermittently stop and advance the article conveying apron respectively in synchronism with the engagement and disengagement of the chest and

buck, said operations being automatically controlled, as will be described later.

Clutch control for ribbon drive

The electric motor 79 (Fig. 1) is supported by the framework. This motor is belted to one pulley 80 of a double pulley unit which is supported for rotation in a bracket 82 fixed to the framework. The other pulley 83 is belted to a pulley 84 (Figs. 1 and 3) mounted for free rotation on a shaft 85 supported for rotation by brackets 54. The driving roll 52 is fixed to this shaft. A friction disk 86 (see Fig. 3) is keyed to the shaft and is adapted to cooperate as a clutch element with a side face of the pulley 84. Freely mounted on the hub of the disk 86 is a circular plate 87 which is anchored against rotative movement by a link 89, see Figs. 1 and 3, which is connected between the plate 87 and the framework of the machine. A thrust bearing 90 is interposed between the plate 87 and the outer face of the disk 86 as shown in Fig. 3. Associated with the plate 87 is another plate 92 which is freely mounted on the shaft. It is held against longitudinal movement on the shaft by a collar 93 and a thrust bearing 94, and it is held against rotative movement by pins 95 which are fixed in the plate 87 and extend through holes in the plate 92. Fixed to the working face of the plate 87 is a diaphragm 96. This is cut out at the center and sealed to the plate 87 around this central hole and also around the outer circumferential edge. Thus the area between these edges forms a diaphragm chamber which is connected with a source of pressure fluid through a cored passage 88 in the plate 87. As shown in Fig. 8, this passage communicates with the valve 35 through conduit 116.

When the diaphragm chamber is supplied with pressure fluid its expansion, working against the plate 92, moves plate 87 to the right (Fig. 3) causing the friction disk to contact with the pulley face and exerting pressure which acts as a clutching means to place the driving pulley 84 and the shaft 85 in cooperative engagement. Through this shaft and the roll 52, motion is imparted to the ribbons, and from the ribbons to the apron. Evacuation of the diaphragm is sufficient to cause release of clutching engagement.

Pressure fluid circuits

Referring to Fig. 8, there are two separate fluid circuits, one furnishing power to the pressure motor 28 and the other to the apron driving clutch 86. In the first the fluid supply line 100 is connected through a conduit 102, a needle valve 103, and a conduit 104 to a combination valve 105. This valve is normally idle, or closed, but when actuated by a solenoid 107 it supplies pressure fluid through conduit 106 to the fluid motor 28. The armature of solenoid 107 is connected to a lever 108 which is pivoted in a bracket 109 and is provided with a spring pressed plunger 110 for abutment with the stem of the valve 105.

In the other fluid circuit the supply 100 is connected through a conduit 112, a pressure regulator 113 and a conduit 114 to the intake side of a combination valve 73. The delivery side of this valve is connected through a conduit 115 to the intake side of the combination valve 35, and the delivery side of valve 35 is connected through conduit 116 to the diaphragm 96 of the air clutch. These two circuits are associated in the operation of the machine as follows:

It will be assumed that the apron is moving, in which case, since both of the valves 35 and 73 are in series, they are open and air pressure is being supplied to the clutch producing a drive connection. When the solenoid 107 is energized by means to be later described to cause a pressure applying operation of the pressure motor 28, the first increment movement of the piston of the motor causes the abutment 25 to be elevated 10 away from the stem of the valve 35, permitting the valve to close. This shuts off the supply and exhausts the operating diaphragm of the air clutch and the drive for the apron is disconnected. A second method of exhausting the 15 clutch diaphragm is achieved by operation of the foot pedal 64 which permits spring actuated closure of valve 73, thereby interrupting the fluid pressure which normally maintains the clutch in engagement.

Electrical circuits

As previously stated, the application of pressure is automatically and synchronously controlled with relation to the spron advance. Movement of the buck to and from pressure engagement controls the movement of the conveying apron as previously described, and in turn, the movement of the apron periodically energizes electrical circuits to control the operation of the pressure fluid motor for pressure application. This control will 30 now be described, with special reference to Fig. 9.

This control is effected through energization of the solenoid 107. It is of electronic form and embodies a time delay circuit. In general, it 35 comprises two electronic tubes 118 and 119 having associated therewith conventional plate and grid circuits. For illustration purposes, these are shown as three-element separate heater alternating current tubes, although it should be understood that certain gas filled four-element tubes will be suitable. Although in practice, a single transformer may be used, for convenience in illustration, separate transformers 120 and 124 are provided, one for each tube circuit. The primaries of these transformers are supplied with line voltage from L₁ and L₂.

The circuit for the plate 128 of the tube 118 is supplied with current from the secondary winding 122 of the transformer 120 by the conductor 129, the relay 130 and the conductor 132. The 50 cathode heating filament 133, as diagrammatically shown, is supplied with current from the secondary 123 of the transformer 120.

The grid 134 is biased with respect to the cathode 135 and the terminal 136 of the plate circuit by a standard voltage-drop grid bias resistor 137. This resistor controls the space current cut-off point of the tube and the tube, thus biased, passes plate current so as to energize relay 130 which holds the armature 138 in the position "A." This 60 is a normal condition, when the work carrying belt is moving.

The circuit for the plate 139 of the tube 119 is supplied with current from the secondary 125 of the transformer 124, by conductor 142, relay 143 and conductor 144. The cathode heating filament 145 is supplied with current from the secondary 126 of the transformer 124. The grid 146 is normally biased with respect to the cathode 147 and terminal 148 of the plate circuit by a standard voltage drop grid bias resistor 149. This resistor controls the space current cut-off point of the tube and the tube, thus biased, passes plate current which energizes the relay 143 thereby 70 holding the armature 150 in the position "A."

This, again, is the normal condition, when the work carrying belt is moving.

In the above arrangement the tube 119 and associated circuits function as a standard electronic switch which picks up an impulse, produced as the metal lacing of the conveyor apron completes a supplementary grid circuit by passing between the conducting elements 43 and 45, and relays it for controlling the operation of the second tube 118 which, through changes in the effects in its plate circuit, functions to produce the actual controlling operation of the machine.

The conducting elements, fingers 45 and plate 43, are connected in a circuit to which current is supplied from the secondary 127 by conductor 152, conductor 153, resistor 154 and conductor 155. When the metal lacing, in its passage, contacts 43 and 45, a supplementary bias is imposed on the grid 146. The potential originating in the secondary 127 is impressed on the grid through conductor 152, conducting elements 45, 47, 43, conductor 153 and resistor 149. This added potential over-biases the grid or, in other words, causes its potential to pass beyond the space current cut-off point, blocking the flow of plate current, which causes the relay 143 to be de-energized and armature 150 to move to position "B." This is of short duration due to the movement of the lacing 47 which coasts past contacting position. But, during the short interval while the lacing 47 closes the circuit and armature 150 is in position B, two effects are produced. First, a circuit is closed from rectifier 186 by way of conductor 156, armature 150, conductors 160 and 162, rheostat 163, resistors 165 and 137 to the grid 134, and from the cathode 135 by wire 159 back to the rectifier. This circuit changes the potential of the grid, adjusting it beyond the space current cut-off point, blocking the flow of plate current and causing the relay 130 to be de-energized, so that armature 138 moves to position B. Consequently, the circuit through coil 107 is completed, and the press begins to close.

The effect upon the relay 130 is maintained by a second circuit which is simultaneously produced by the operation of the armature 150. This circuit is from the rectifier 186 by conductor 156, armature 150, conductor 160, condenser 166 to grid 134 and back to the rectifier by way of the cathode 135 and conductor 159, as before. This circuit, when closed, has the immediate effect of charging condenser 166. Thus, when the lacing passes the contacts 43, 45, opening the original circuit including those contacts, and causing armature 150 to move back to position A, the potential applied to the grid 134, now at a value beyond the space current cut-off point, is maintained by the potential of condenser 166 exercised through a circuit from one side of said condenser to the grid and from the other side of the condenser by conductors 160, 162, rheostat 163, resistor 165 to the cathode. Therefore, coil 107 remains energized, the operating motion of the press is completed, and the press remains closed until coil 107 is de-energized by leakage of the charge in condenser 166 through resistors 137 and 165, and rheostat 163, until the grid potential has been adjusted beyond the space current cut-off point, but in the opposite direction, so that plate current again begins to flow to the coil 130, energizing said coil and returning armature 138 to position A. This opens the circuit to coil 107 and the press opens.

The rate of discharge of the condenser 166 is controlled by the position of the conducting arm 164 of the rheostat 163. When the arm is on point 2, the discharge rate is controlled by the resistor 165 and in actual practice, this provides a pressing period of two seconds. On point 3 the rate of discharge is governed by resistor 165 and the resistor section 2 to 3 of the rheostat. In positions 4, 5, etc., a section of resistance is added, in each case, to prolong the pressing period proportionately.

The conducting plate 43, as will be seen in Fig. 4, is completely insulated from the frame by insulating washers 157 and an insulating collar 158, so that when the metal lacing engages the fingers 45, a circuit is completed and current must pass between the fingers and the conducting plate.

In order to assure a uniform initial charge on the condenser 166, the charging current for this condenser is rectified in the tube 186 and the voltage is regulated by the tube 187. The primary of the transformer 184 is supplied with current from the lines L₁ and L₂ in the same manner as 120 and 124 are supplied.

The numeral 79 designates the apron drive motor which, as shown in Fig. 9, is connected directly to the three-phase alternating current power source L₁, L₂ and L₃ under the control of a switch 270 which is also ahead of the control circuits just described.

One feature of the control not described above involves a switch 175. This switch is connected between the conductors 140 and 160 and its purpose, when closed, is to short-circuit the condenser 166 to produce a rapid discharge and thereby permit opening of the press, if such is desired, before the operation is automatically terminated by the automatic control. When closed, the switch 175 prevents energization of the solenoid 107 because it short-circuits the supplementary grid circuit of the tube 118 and also prevents charging of the condenser 166. The apron, however, continues to move and therefore a means is provided to clear the conveyor system of any articles in the press. Such an operation would be desirable at the end of a lot so that all pieces contained in that lot would be cleared from the press before operation on the next lot was begun. It is also desirable at the end of the day's operation. In the normal automatic operation of the machine, this switch is open.

Resistor 188 is provided in series with switch 175 as a load for the power supply 185 when the switch 175 is closed. Its value, relative to the other resistors in the circuit, is small enough to prevent adverse effect in the operation of the apparatus.

In the embodiment illustrated in the accompanying drawings the apron is divided into four sections by the metal lacing, that is to say, that there are four of these lacing connections which constitute four control points in the full length of the apron. Of course, the apron construction might comprise a continuous strip of material provided with four conductors spaced like the metal lacing. In the stopped position of the apron during operation of the press, one of these will lie approximately at a position 170 (Fig. 1). The trailing edge of this one has just passed the conducting point 43-45 and has initiated a press operation. The trailing edge of the next one in the direction of travel of the 75 apron, which is counterclockwise, as viewed in

Fig. 1, is at a point 171. Each time the press operates, the next lacing in succession will initiate the next press operation, that is, the one then at position 173 will pass between the conducting plates and fingers 43 and 45 and will stop at the position 170, the one then at 170 would take the position 171, and the one at 171 would take position 172, and so on. In this way, one section of the apron in the idle position is always over the dressing table and the next section is between the buck and the chest.

Since the buck 18 is usually heated there is a very definite heating effect by radiation from the lower surface of the buck. In the intermittent operation of the conveyor apron as described, the article or articles issuing from the ironing or pressing position, is carried around underneath the buck, and there pauses temporarily during the next succeeding pressing operation. The radiant heat from the lower buck surface is therefore effective to produce an after-drying effect which is immediately subsequent to the pressing operation. This removes the residual condensed moisture usually encountered at the end of a pressing operation, and also keeps the apron dry.

While those skilled in the art are familiar with various means for heating either or both of the pressing members, I show in Figs. 1 and 3 conduit means 176 for conducting steam to the chest 16 and flexible coupling means 177 for carrying steam from the same source to the buck 18. The steam outlet or return is by way of conduit 178 from the chest and flexible coupling 179 from the buck.

Operation

In describing the operation of the press, it will be assumed that the parts, as shown in all of the views, are in a position that they normally occupy at the beginning of a day's operation. At this time the switch 175 is closed, having been put in that condition the night before when the press was cleared of all articles in the conveyor system. The rheostat 163 is at zero and the switch 270 is open. Under these conditions, the control apparatus is as shown in Fig. 9. To set the machine into operation, the operator closes the main switch 270. This energizes the motor 79 and starts the apron in motion. It also energizes the tube circuits which establish the normal bias on the tubes, the relays are energized and the armatures 138 and 150 are closed being thereby moved to the position "A." This, of course, opens the circuit to the solenoid 107 so that the buck remains in the lower position. The operator then sets the rheostat 163 to the position for the pressing time desired. For example, assume this is three seconds, the conductor 164 is moved to terminal 3. The switch 175 is then opened. When the next belt lacing 47 passes between the conducting members 43 and 45, the circuit to solenoid 107 is closed and consequent operation of servomotor 28 causes the buck to move toward the chest, and, since valve 35 is thereupon permitted to close by spring actuation, the apron stops and pressure is applied. The operator then grasps an article by one edge and applies it to the apron section on the table 38 with the remote edge beneath the clamping bar 59. She then depresses the pedal 64 bringing the cross bar 61 into engagement with the said rear edge. She then smoothes off the article and removes her foot from the pedal, permitting the clamping bar to return.

We will now follow through an operation of the control mechanism of Figs. 8 and 9 up to this point, directing attention to the interaction between the electronic circuits and the fluid pressure circuits. When the belt lacing passed between conductors 43 and 45, the supplementary grid bias was established for the tube 119 overbiasing the grid thereof blocking the flow of plate current and causing the armature 150 to move to position "B." This established the supplementary grid circuit for tube 118, blocking the flow of plate current to relay 130, completing a circuit to the coil 107, and simultaneously charging condenser 166. When the lacing 47 moved out of contact with the contacting elements, relay 143 was re-energized, armature 150 moving to position A, breaking the supplementary grid circuit for tube 118, but leaving the condenser 166 effective thereon and discharging, until finally by sufficient discharge of said condenser, the grid potential for tube 118 was again adjusted to the current conduction point, causing armature 138 to return to its A position, de-energizing coil 107 and permitting the press to open. When the buck was raised into pressure engagement, the valve 35 was permitted to close, evacuating the diaphragm chamber of the air clutch which caused the apron to stop. As the buck moved upwardly, the clearance space between yoke 22 and bar 30 was closed and the clamping bar 30 became effective to hold the drive ribbons.

The rate of discharge of the condenser in this case is controlled by the resistor 165 in conjunction with the resistor section 2 to 3 of the rheostat 163, which produces a time period of three seconds.

As the buck approaches the press open position, the drive ribbons are released by the clamping bar 30 and the valve 35 is again opened, permitting the passage of pressure fluid to energize the diaphragm of the air clutch and thereby engage the clutch members to again connect the drive unless the foot pedal 64 is still depressed by delay of the operator in arranging the next lay, in which case the clutch members will not engage until the foot pedal is released. As seen in Fig. 8 depression of the foot pedal allows valve 73 to be closed to fluid pressure and opened to exhaust, and when the buck is in lower position thereby depressing stem 36 of valve 35, the clutch diaphragm is open to exhaust through valves 35 and 73. Release of foot pedal 64 causes valve 73 to be closed to exhaust and permits fluid pressure through lines 114 and 115 to again actuate the clutch diaphragm. As the next metal lacing moves between the conducting plate 43 and the fingers 45, the above described cycle of operation is repeated.

If for any reason the dressing operation had taken a longer time than was permitted by the automatic control, the buck would lower in the usual way under the control of the timer, but the apron would not continue its movement until the operator had released the pedal 64.

After completion of the pressing operation the finished article is carried to the left (Fig. 1) and downwardly around curved plate 48, in which region it is received between the lower run of apron 46 and the upper run of driving ribbons 34. By successive cycles of operation, each involving a controlled increment of apron advance as hereinabove described, the article progresses past roll 49 and thereafter upwardly around roll

50 to the delivery and loading station above table 51. The article at this point is removed by the operator prior to disposing a new article on the apron.

In the embodiment so far discussed, the initiation of the operative cycle, beginning with a pressing operation, is effected by passage of one of the conductor elements 47 between contacts 43 and 45. As has been explained the elements 47 are preferably carried by the apron 46. A 10 somewhat modified embodiment is shown in Fig. 10, which is a fragmentary plan view, somewhat enlarged, as seen from immediately above idler roll 50 which carries the apron immediately adjacent the operator's position. In this exemplification an endless belt 201 is movable in synchronism with, and preferably in the plane of, an apron 202. For convenience the belt passes over the curved plate 48 and the spring plate 51, and over the same respective sequence of rolls 20 15 as does the apron so that the belt and apron start, travel, and stop simultaneously. Conducting elements 203 are carried by the belt, instead of by the apron as in the embodiment heretofore described, and, as in that embodiment, elements 203 may also serve as belt lacing means although of course they may be conducting members integral with or carried by the belt.

The contacting elements 43 and 45 (not shown in Fig. 10) in this embodiment are mounted laterally so as to maintain contact with the belt 201 instead of with the apron. In this embodiment, therefore, the work carrying apron may be of conventional construction, permitting immediate replacement from standard stock.

When the control is initiated from a belt of this nature the belt may, if desired, be supported and driven by a plurality of pulleys or rolls, in part or completely distinct from those carrying the apron provided of course that the belt and apron drives are properly synchronized to permit the controlled operative cycle hereinabove described in detail.

What I claim is:

1. A fabric pressing apparatus comprising co-acting pressing elements, an endless, movable work-carrying apron having a portion thereof positioned between said pressing elements, driving means for said apron, power means for producing relative movement between said pressing elements whereby they engage said apron in pressing relationship, electrical circuit means for initiating and terminating operation of said power means, means operated in timed relation with movement of said apron for actuating said circuit means periodically to initiate operation of said power means whereby said elements periodically assume pressing relationship, and automatic electric timing means, in operative relationship with said circuit actuating means, for actuating the same to deenergize and terminate operation of said power means after a pressing period of preset length whereby said pressing elements separate, and terminate pressing relationship.

2. A fabric pressing apparatus comprising co-acting pressing elements, an endless, movable work-carrying apron consisting of a plurality of segments united by electrical current conducting material, said apron having a portion thereof positioned between said pressing elements, driving means for said apron, power means for producing relative movement between said pressing elements whereby they engage said apron in pressing relationship, electrical circuit means for

initiating and terminating operation of said power means, said circuit means including a pair of contact members in slidably engagement with said apron whereby passage of said current conducting portions of said apron across said contact members periodically completes said circuit means and energizes said power means to cause the pressing elements to approach and assume pressing relationship, and automatic electronic timing means in operative association with said contact members for actuating said circuit means to deenergize and terminate operation of said power means after a pressing period of preset length, whereby said pressing elements separate, and terminate said pressing relationship.

3. A fabric pressing apparatus comprising co-acting pressing elements, an endless, movable work-carrying apron having a portion thereof positioned between said pressing elements, driving means for said apron including an endless ribbon movable from a powered source, said apron being in frictional contact with said ribbon over a portion of their respective paths of travel whereby said apron is movable concurrently with said ribbon solely through said frictional contact, means responsive to apron movement for moving one of the pressing elements into and out of pressing engagement with the other, and means responsive to motion of said movable pressing element for alternately instituting and interrupting operative connection between said endless ribbon and said powered source.

4. A fabric pressing apparatus comprising co-acting pressing elements, an endless, movable work-carrying apron having a portion thereof positioned between said pressing elements, driving means for said apron including an endless ribbon movable from a powered source, said apron being in frictional contact with said ribbon over a portion of their respective paths of travel whereby said apron is movable concurrently with said ribbon solely through said frictional contact, means responsive to apron movement for moving one of the pressing elements into and out of pressing engagement with the other, and means responsive to motion of said movable pressing element for rendering said endless ribbon drive inoperative while said pressing elements are in pressing engagement.

5. A fabric pressing apparatus comprising co-acting pressing elements, an endless, movable work-carrying apron having a portion thereof positioned between said pressing elements, driving means for said apron including an endless ribbon movable from a powered source, said apron being in frictional contact with said ribbon over a portion of their respective paths of travel whereby said apron is movable concurrently with said ribbon solely through said frictional contact, means for moving one of the pressing elements into and out of pressing engagement with the other, means responsive to motion of said movable pressing element for rendering said endless ribbon drive inoperative while said pressing elements are in pressing engagement, and clamping means, operatively associated with said movable pressing element, for gripping said driving ribbon during pressing engagement to further prevent motion of said ribbon during said pressing engagement.

6. A fabric pressing apparatus comprising a dressing table obliquely inclined towards an operator's station, a pair of cooperating pressing elements in juxtaposition to the edge of said table remote from said operator's station, an endless,

work-carrying apron movable in a closed path and having the upper run thereof movable from a dressing position above said table to a pressing position between said pressing elements, and spring impelled backing means in contact with the under surface of said apron above said table to maintain said apron in taut condition.

7. A fabric pressing apparatus comprising a dressing table obliquely inclined towards an operator's station, a pair of cooperating pressing elements in juxtaposition to the edge of said table remote from said operator's station, an endless, work-carrying apron movable in a closed path and having the upper run thereof movable from a dressing position above said table to a pressing position between said pressing elements, spring impelled backing means in contact with the under surface of said apron above said table to maintain said apron in taut condition, driving means for advancing said apron along said path, means responsive to apron movement for moving one of the pressing elements into and out of pressing engagement with the other, and means responsive to motion of said movable pressing element for rendering said driving means inoperative while said pressing elements are in pressing engagement.

8. A fabric pressing apparatus comprising a dressing table downwardly inclined towards an operator's station, a pair of cooperating pressing elements in juxtaposition to the edge of said table remote from said operator's station, an endless work supporting apron movable in a closed path from a dressing position above said table to a pressing position between said pressing elements, clamping means for holding articles to be pressed on the dressing portion of said apron during the dressing operation, driving means for imparting motion to said apron, and means responsive to the movement of said clamping means for deenergizing said driving means while said clamping means is in article-clamping position.

9. A fabric pressing apparatus comprising a dressing table downwardly inclined towards an operator's station, a pair of cooperating pressing elements in juxtaposition to the edge of said table remote from said operator's station, an endless work supporting apron movable in a closed path from a dressing position above said table to a pressing position between said pressing elements, clamping means for holding articles to be pressed on the dressing portion of said apron during the dressing operation, driving means for said apron, power means for producing relative convergent and divergent movement of said pressing elements with relation to each other and to said apron, means operatively associated with said clamping means for rendering said apron driving means inoperative during the dressing operation, electrical circuit means for initiating and terminating operation of said power means, means carried by said apron for actuating said circuit means during movement of said apron whereby said pressing elements periodically converge into pressing relationship, automatic electronic timing means in operative relationship with said circuit actuating means for operating the same to deenergize and terminate the operation of said power means after a pressing period of preset length, whereby said pressing elements diverge from pressing relationship, and means for suspending operation of said apron driving means during the

period when said pressing elements are in engagement with said apron.

10. A fabric pressing apparatus comprising cooperating pressing elements, an endless, movable work-carrying apron having a portion thereof positioned between said pressing elements, endless belt means movable in the plane of, and in synchronism with, said apron, driving means for simultaneously moving said belt and said apron, power means for producing relative convergent and divergent movement of said pressing elements with relation to each other and to said apron, electrical circuit means for initiating operation of said power means, means carried by said belt means for actuating said circuit means during movement of said apron whereby said elements converge periodically into pressing relationship, and automatic electronic timing means in operative relationship with said actuating means for deenergizing said power means after a pressing period of preset length, whereby said pressing elements diverge from pressing relationship, and means for suspending operation of said apron driving means during the period when said pressing elements are in operative engagement.

11. Fabric pressing apparatus, comprising relatively movable pressing members, operating means therefor, an endless movable work carrying apron having a portion traveling between said pressing members, driving means therefor, actuating means for causing operation of said operating means, control means operated by and synchronously with apron travel and effective upon said actuating means to cause operation of said operating means to close the press, and separate timing means whose operation is initiated by and synchronously with apron travel and effective upon said actuating means to open the press after the lapse of a predetermined time delay period.

12. Fabric pressing apparatus of the character described in claim 11, in which said timing means is adjustable to vary the time delay period.

13. Fabric pressing apparatus, comprising relatively movable pressing members normally biased toward open position, an endless, movable work carrying apron having a portion positioned between said pressing members, driving means for said apron, power means arranged when operated to overcome said bias and close the pressing members upon the apron and the work carried thereby, electric circuit means for initiating and terminating operation of said power means, means operated synchronously with apron travel for controlling said circuit means to cause initiation of operation of the power means and thereby close the press, and automatic electric timing means operatively related to said circuit means for causing the same to terminate operation of the power means after the lapse of a predetermined time delay period, whereby the pressing members separate and the pressing operation is terminated.

14. Fabric pressing apparatus of the character described in claim 13, in which said timing means is adjustable to vary the time delay period.

15. Fabric pressing apparatus, comprising relatively movable pressing members, operating means therefor, an endless movable work carrying apron having a portion traveling between said pressing members, driving means therefor, said apron being provided at regular intervals with control members formed of current conducting

material, electric circuit actuating means for causing operation of said operating means and including circuit contacts lying in the path of motion of said control members and adapted to complete a circuit of said circuit means when engaged by one of said control members, thereby causing operation of said operating means to close the press, and timing means also effective upon said actuating means to cause operation of said operating means to open the press after the lapse of a predetermined time delay period.

16. Fabric pressing apparatus, comprising relatively movable pressing members, operating means therefor, an endless movable work carrying apron having a portion traveling between said pressing members, driving means therefor, actuating means for causing operation of said operating means, means operated synchronously with apron travel and effective upon said actuating means to cause operation of said operating means to close the press, timing means also effective upon said actuating means to cause operation of said operating means to open the press after the lapse of a predetermined time delay period, work clamping means, operator-operated means for actuating said clamping means, and means controlled thereby for suspending operation of said

10 apron driving means while the clamping means is effective.

17. Fabric pressing apparatus, comprising relatively movable pressing members normally biased toward open position, an endless, movable work carrying apron having a portion positioned between said pressing members, driving means for said apron, power means arranged when operated to overcome said bias and close the pressing members upon the apron and the work carried thereby, electric circuit means for initiating and terminating operation of said power means, means operated synchronously with apron travel for controlling said circuit means to cause initiation of operation of the power means and thereby close the press, automatic electric timing means operatively related to said circuit means for causing the same to terminate operation of the power means after the lapse of a predetermined time delay period, whereby the pressing members separate and the pressing operation is terminated, work clamping means, operator-operated means for actuating said clamping means, and means controlled thereby for suspending operation of said apron driving means while the clamping means is effective.

20 25 JOHN E. PRESTON.
